UNITED STATES PATENT OFFICE

OSCAR CARLSON, OF MINNEAPOLIS, MINNESOTA, ASSIGNOR TO REEL-MOP CORPORATION, OF MINNEAPOLIS, MINNESOTA, A CORPORATION OF MINNESOTA

COMBINED MOP HEAD AND WRINGER

Application filed September 16, 1929. Serial No. 392,831.

My present invention has for its object to provide a simple and highly efficient mop head and wringer and is in the nature of an improvement on or a refinement of the mop head and wringer disclosed and broadly claimed in my United States Letters Patent 1,683,655 of date September 11, 1928.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the mop head and wringer showing the manner in which the same is held to wring a mop or unwind a mop therefrom, after the same has been wrung;

Fig. 2 is a view corresponding to Fig. 1, but on a smaller scale, showing the mop wound on the wringing roll;

Fig. 3 is a perspective view of the mop removed from the mop head and wringer;

Fig. 4 is a fragmentary detail view of the mop in section taken on the line 4—4 of Fig. 3, on an enlarged scale;

Fig. 5 is a detail view principally in section taken on the line 5—5 of Fig. 1, on an enlarged scale;

Fig. 6 is a view partly in elevation and partly in central section taken on the irregular line 6—6 of Fig. 1, on an enlarged scale;

Fig. 7 is an enlarged fragmentary detail view principally in section showing the handle in an operative position;

Fig. 8 is a detail view principally in section taken on the line 8—8 of Fig. 6;

Fig. 9 is a fragmentary detail view principally in section taken on the line 9—9 of Fig. 6, on an enlarged scale;

Fig. 10 is a detail view in section taken on the line 10—10 of Fig. 7;

Fig. 11 is a perspective view of the sections of the mop head as they appear before being assembled, some parts being broken away and another part being shown in a different position by means of broken lines;

Fig. 12 is a fragmentary perspective view

of the back section of the mop head to illustrate one of the spring abutments; and

Fig. 13 is a view partly in elevation and partly in section taken on the line 13—13 of Fig. 2, on an enlarged scale and further showing a cover for the mop that is wound thereon.

The mop head comprises front and back substantially duplicate sections 15—16, respectively, each of which is stamped and pressed from a single sheet of metal. These mop head sections 15—16, when assembled, form a horizontal tubular body 17 having open ends, an upstanding socket 18, at the longitudinal center of said body, and a long sleeve seat 19 that is rectangular in cross section.

An upper yoke 20 formed from a flat strip, is rigidly secured to the body 17 by having its transverse portion mounted in the seat 19, see Fig. 9. Primarily, the lower part of the back section 16 is straight, as shown by full lines in Fig. 11, to receive the transverse portion of the yoke 20 between the sections 15—16 and thereafter folded, as shown by broken lines in Fig. 11 and interlocked at 21 with the front section 15 to connect said sections at their lower end portions.

The length of the body 17 is such as to extend the full distance between the prongs of the yoke 20 and thereby hold said yoke against longitudinal shifting movement in the mop head.

The lower end of the mop handle 22 is telescoped into the socket 18 and rigidly secured thereto by a rivet 23, which also rigidly connects the sections 15—16. In each end of the tubular body 17 is a pair of diametrically opposite internal spring bosses 24, the purpose of which will presently appear.

A wringing roll 25 of relatively small diameter is journaled in the prongs of the yoke 20 and a crank arm 26 is rigidly secured to the right-hand end thereof outward of said yoke. The upper end portion of the crank arm 26 is folded outwardly upon itself to form a rectangular bearing 27 having a pair of axially aligned and axially spaced bore-like seats 28. A handle 29 is provided for the crank arm 26 and includes a stem 30 turnably mounted in the seats 28 with freedom for end

- wise sliding movement to and from an operative position. On the outer end of the stem 30 is a hand-piece 31 in the form of a disc having an inwardly rolled capping flange 32 for the bearing 27 when the handle 29 is in an inoperative position, see Fig. 6. The stem 30, when the handle 29 is in an inoperative position, is adapted to be projected into the respective end of the tubular body 17.
- 10 By reference to Fig. 6, it will be noted that the crank arm 26 is laterally and inwardly offset at 33 so that when said handle 29 is in an inoperative position, its hand-piece 31 is substantially at the outer face of said crank arm and does not project materially outward thereof and thus will not interfere with mopping action when working near a mop board or the like.

On the inner end of the stem 31 is a stop flange 34, arranged to engage the bearing 27 and limit the movement of the handle 29 to an operative position. Adjacent to the stop flange 34 is an annular lock-groove 35 and cooperating therewith to yieldingly hold the handle 29 in an operative position, is a coiled spring, 36 mounted in a seat within the bearing 27, and under strain to project into said lock-groove 35 when aligned therewith, see Fig. 7. The purpose of thus locking the handle 29 in an operative position is to prevent the same from being pressed inwardly during the rotation of the crank arm 26 and interfere with the movement thereof.

A clamp 37, cooperating with the wringing roll 25, is provided for detachably securing a mop thereto. This clamp 37, as shown, comprises a bar 38, which is segmental in cross-section, substantially concentric with the wringing roll 25 and extends the full distance between the prongs of the yoke 20 with a working fit therebetween. Rigidly secured to the clamping bar 38 is a pair of radially projecting screw-studs 39 which extend loosely through diametrically extended bore-like seats in said roll and have applied thereto thumb-nuts 40. These thumb-nuts 40 impinge against recessed seats provided therefore in the opposite side of the wringing roll 25 from the clamping bar 38, see Fig. 5.

50 A mop 41 is attached to the wringing roll 25, by means of the clamp 37 and, as shown, is woven in the form of a tube and has a loop 42 of canvas or other suitable material sewed to one end thereof, see Figs. 3 and 4. To attach the mop 41 to the wringing roll 25, the clamping bar 38 which has previously been detached from said roll, is inserted endwise into the loop 42 from one end thereof and its screw studs 39 are inserted through holes in the transverse portion of said loop which is between the wringing roll 25 and clamping bar 38. The screw-studs 39 are then inserted through their seats in the wringing roll 25 and the nuts 40 applied thereto with sufficient force to draw the loop

38 onto the wringing roll 25 and securely clamp the same between said bar and wringing roll.

Cooperating with the wringing roll 25 is a squeezing abutment in the form of a roll 43 having a diameter considerably larger than that of said wringing roll. This squeezing roll 43 has on its ends trunnions 44 journaled in the prongs of a lower yoke 45 mounted between the prongs of the yoke 20. Said trunnions 44 project into longitudinally extended slots 46 in the prongs of the yoke 20 and hold the lower yoke 45 for straight line movement in the plane of the yoke 20. There is sufficient clearance between the prongs of the yokes 20 and 45 to permit angular movement of the squeezing roll 43 in respect to the wringing roll 25.

By means of a large relatively stiff coiled spring 47, the squeezing roll 43 is yieldingly pressed toward the wringing roll 25 for action on the mop 41 to squeeze the water therefrom as said wringing roll is rotated to wind said mop thereon. This spring 47 is mounted in the socket 18, encircles an upright stem 48 and is compressed between the lower end of the handle 22 and a washer 49 on said stem. Said stem loosely extends through aligned apertures in the lower member of the seat 19 and the transverse portion of the yoke 20, at the longitudinal center thereof. The lower end portion of the stem 48 loosely extends through an aperture in the transverse portion of the yoke 45, see Fig. 6, and has applied thereto an adjustable abutment 50, in the form of a thumb-nut, having screw-threaded engagement with said stem and impinges against the upper surface of said yoke. Obviously, by adjusting the nut 50, on the stem 48, the tension of the spring 47 may be varied at will.

By reference to Fig. 6, it will be noted that the slots 46 limit the approaching movement of the squeezing roll 43 toward the wringing roll 25. As the mop 41 is wound on the wringing roll 25, which is in contact with the outer surface of said mop, the squeezing roll 43 is moved away from the wringing roll 25 under the increasing diameter of said mop against the tension of the spring 47.

As previously stated, the squeezing roll 43 is free for angular movement in respect to the wringing roll 25 and hence will automatically adjust itself to the mop 41 longitudinally thereof.

To wring the mop 41, the mop head and wringer is held and the wringing roll 25 operated, as shown in Fig. 1, and to unwind said mop therefrom, it is only necessary to operate the crank arm 26 in a reverse direction. During mopping action, the handle 29 is moved in an inoperative position as shown in Fig. 6, to lock the wringing roll 25 against rotation.

It will be noted that only one pair of spring

bosses 24 are in use and the other pair of spring bosses 24 is simply to give the mop head a symmetrical appearance and permit the members 15-16 to be assembled either at the front or at the back of said mop head.

As the diameter of the cylindrical body 17 is materially larger than that of the stop flange 34, the stem 31 will freely enter said body without being brought into true axial alignment therewith and thereafter be centered by the engagement of said stop flange with the adjacent pair of spring bosses 24. These spring bosses 24 will yield to permit the stop flange 34 to pass the same and thereafter engage the stem 31 and hold the same against lateral movement thereof which in turn holds the crank arm 26.

The mop 41, when wound, as shown, in Fig. 2, is well adapted for use in polishing floors and the like and in such use a piece of cheese cloth or other material 51 will be wound thereon to form a casing therefor, see Fig. 13. To thus apply the material 51 around the mop 41, one end portion thereof is inserted into the tubular lower end of the mop 41 before said mop is completely wound on the wringing roll 25 and thereafter said roll is operated to wind the material 51 on the mop 41 so as to form two or three thicknesses thereof. The outer end portion of the material 51 is held from unwinding by the squeezing roll 43.

What I claim is:

1. A mop head and wringer comprising a head having a pair of prongs, a mop holding roll journaled on said prongs, a crank arm on the roll for rotating the same to wind a mop thereon, a handle on the crank arm comprising a hand-piece equipped stem mounted for endwise sliding movement in the arm and supporting the handle for movement to and from an operative position, said stem having an annular lock groove in its inner end portion and a yielding member on the crank arm arranged to be projected substantially radially into the lock groove to hold the handle in an operative position.

2. A mop head and wringer comprising a head having a pair of prongs, a mop holding roll journaled on the prongs, a crank arm on the roll for rotating the same to wind a mop thereon, the outer end portion of said arm being folded upon itself and the members laterally spaced to form a bearing having a pair of axially aligned and axially spaced seats, a handle for the arm comprising a hand-piece equipped stem slidably mounted in said seats and supporting a handle for movement to and from an operative position, said stem having an annular groove in its inner end, and a spring mounted in a seat between the bearing members and under strain to project into said groove and hold the handle in an inoperative position.

3. A mop head and wringer comprising

a head having a pair of prongs, a mop holding roll journaled on the prongs, a crank arm on the roll for rotating the same to wind a mop thereon, the outer end portion of said arm being folded to form a bearing having a pair of axially aligned and axially spaced seats, a handle for the arm comprising a hand-piece equipped stem slidably mounted in said seats and supporting a handle for movement to and from an operative position, said handle having a cavity in its inner face into which the bearing projects when the handle is in an inoperative position.

4. A mop head and wringer comprising a head having a pair of prongs, a mop holding roll journaled on the prongs, a crank arm on the roll for rotating the same to wind a mop thereon, the outer end portion of said arm being folded to form a bearing having a pair of axially aligned and axially spaced seats, a handle for the arm comprising a hand-piece equipped stem slidably mounted in said seats and supporting a handle for movement to and from an operative position, a stop member on the stem for limiting the movement of the stem in the bearing during the movement of the handle to its operative position, a pair of diametrically opposite internal spring bosses on the tubular member, said bosses being arranged to yield and permit the stop member to pass the same during the movement of the handle to an inoperative position and yieldingly hold the stem.

5. The combination with a relatively thick flat mop and a relatively thin strip that is folded upon itself to form a loop, the longitudinal edge portions of which overlap the mop at one end and are secured thereto, of a mop head having a wringing roll, means for rotating the roll, a clamp inserted through the loop and applied to the roll for clamping the transverse portion of the loop between the roll and loop with the mop entirely free from the roll and clamp.

In testimony whereof I affix my signature.

OSCAR CARLSON.
